UNITED STATES PATENT OFFICE.

RUSSELL V. APPLETON, OF INGLEWOOD, CALIFORNIA.

TRAIN STOP AND SIGNAL SYSTEM.

Application filed April 13, 1927. Serial No. 183,340.

This invention relates to an improved inductive train stop system, and more particularly to the combination with a block signal system of a single element train stop, and position indicating mechanism in the locomotive cab, designed to give the operator a closer vision of track conditions and stop locations, and to doubly warn of the approach to occupied territory by signals, and brake applications which can be reset while running under caution conditions only, but under stop conditions can only be reset after the vehicle is brought to a complete halt.

Briefly described, the system provides means whereby a wayside track caution signal is given at the entrance to the block preceding the block occupied by a train or other obstruction. In addition, a caution indication signal is given in the cab, not only in the first block preceding the occupied block, but also a repeating caution signal for prior acknowledgment by the operator is given in the second preceding block at the entrance to which the usual "proceed" signal is displayed at the wayside. At the exit end of each of the two blocks preceding the occupied block, a stop signal will be flashed in the cab, and a brake application will take place unless forestalled by a manually operated acknowledgment switch in the cab. Means in the cab is provided whereby the brakes may be released and reset if their application is not forestalled in time, provided the train is merely in a caution block, but the brakes can only be reset after the train is completely halted in case the train is in a stop block or an obstruction occurs in the block then occupied by the train. To accomplish the above, one track and one line relay for each block are used to furnish, from a single alternating current source, either normal polarity current to the entire block, or adverse polarity current to a portion of the block, according to track conditions. The wayside semaphore signal systems also are actuated from the same power source. A single power source on the locomotive furnishes current for the brake releasing means, and the signal lights in the cab, these being controlled by a relay energized through an amplifier from current induced from the tracks, and also by certain acknowledgment switches

which must be manipulated by the operator to forestall the brake applications, or to reset the brakes.

One object of this invention is to provide a train stop of this class which may be operated in combination with or without the wayside semaphore or other signaling system.

Another object is to provide an apparatus for automatically controlling the stopping of the train, in combination with cab colored lights indicating the advance condition of the track and brake application points, so that the operator may forestall an automatic brake application if alert at the brake application points.

Another object is to provide an apparatus of this type in which the train when stopped cannot be started again without properly setting the engineer's brake valve and then manipulating fixed releasing means, located below the locomotive.

Another object is to provide an improved amplifying circuit by means of which the electrical energy induced from the track is amplified and converted into two control circuits for energizing the controlling relay on the locomotive.

Another object is to provide novel means whereby, when the engine passes over a clear intermittent braking point on the track, and a sudden change in track conditions occur, a brake application will immediately take place instead of waiting until the next intermittent braking point is occupied.

Another object is to provide an apparatus of this class, in which the operator by controlling the forestalling switch can continue when the train occupies non-electrified track.

Another object is to provide means for supplying one pulsating current to the track rails with triple controlling characteristics.

Another object is to provide such an apparatus wherein a caution signal is given prior to the necessity for use of the acknowledgment switch.

Another object is to provide such an apparatus wherein a brake application occurs upon foreign current interference.

Other objects and advantages of this invention will be apparent from the following detailed description of one system and

combination of parts involving the principles of this invention.

In the accompanying drawings:

Fig. 1 is a diagrammatic layout showing 5 the track apparatus, the wayside signals, and the operating circuits therefor.

Fig. 2 is a diagrammatic illustration of 10 the mechanism carried by the locomotive, including the mechanism for receiving and amplifying the control current from the trackway, the brake control mechanism, the position-indicating signals in the cab, and the 15 control circuits for this mechanism.

Fig. 3 is a detail sectional view of a modified form of acknowledgment switch.

Fig. 4 is a view illustrating diagrammatically and in detail perspective a form of 20 rotary interrupter for providing the pulsating direct current from the original alternating current.

Fig. 5 is a series of diagrams illustrating the relation between the various alternating, pulsating and induced currents.

Referring first to Fig. 1, a stretch of 25 trackway is indicated, along which traffic will normally proceed in the direction of the arrows, this trackway comprising the rails R and R', each rail being separated at intervals by insulation 1, so that the trackway 30 is divided into a series of similar sections or "blocks", each block being insulated from the adjacent blocks. The individual rails composing each line of track-rail R and R' 35 may be suitably bonded together, especially at frogs or cross-overs, so that each rail will form a continuous conductor from one end of the block to the other. The several blocks will normally be of substantially equal lengths, for example, about 4000 feet, 40 although this length may be either increased or decreased without departing from the principles of the invention. In Fig. 1 we have illustrated parts of four blocks, including the entrance end of block 5 1, all of blocks 2 and 3, and the exit end of block 4. Blocks 1, 2 and 3 are designated as a "stop" block, a "caution" block, and a "proceed" block, respectively, these terms being merely relative and depending on the fact that a train now occupies block 1, as indicated diagrammatically by the wheels and axle shown at B. It should be here understood that all blocks and their associated mechanisms, are duplicates of one another, and that any block may assume the characteristics of a stop-block or a proceed-block, according to the positions of trains or other obstructions in one or more of these blocks.

An alternator, A, located at any convenient point, delivers suitable alternating current through the conductors 2 and 3 to the main line conductors 4 and 5 which extend substantially parallel with the several blocks. In each block the traffic signalling

apparatus and circuits therefor are identical with the apparatus and circuits therefor in every other block. Therefore, a detailed description of the apparatus and connections in one block will suffice for all. As 70 here shown, the apparatus and connections associated with the entrance end of block 1 and the exit end of block 2, are indicated by unprimed reference characters, the corresponding parts for blocks 2 and 3 being 75 indicated by primed reference characters, and the similar reference characters for blocks 3 and 4 being double-primed.

The primary P of a transformer located adjacent the exit end of block 2, is energized through leads 6 and 7 extending to the main power lines 4 and 5, respectively. This transformer has a signal secondary SS and two similar track secondaries TS and RS. The polarized three-position line relay C, which is an induction motor relay with two energizing circuits, has a pivoted three-position armature 8^a adapted to open or close a signal circuit hereinafter described and also a pair of similar three-position pivoted armatures 8^b and 8^c. The armatures 8^a, 8^b and 8^c will be swung to the right when coil 8 of relay C is receiving so-called normal polarity current, and will be reversed or swung to the left when the relay is receiving adverse polarity current. The coil 8^c of relay C is constantly energized by alternating current derived from the signal secondary SS. When the relay C is deenergized, the armatures 8^a, 8^b and 8^c 100 will fall to a third or intermediate position.

The coil 11 of a track relay D is connected by wires 9 and 10 across the rails R and R' at the entrance end of block 1. The relay D is provided with a neutral armature having three contact bars 11^a, 11^b, and 11^c, respectively, which are each held up to one circuit-making position when the relay D is energized, and fall to a different position when the relay is deenergized.

An interrupter K (shown in detail perspective in Fig. 4, and indicated diagrammatically in Fig. 1), is utilized to convert alternating current induced from the primary P into a pulsating direct current in the rails R and R'. In the form indicated, a coil 200 is mounted to rotate between the poles of a stationary permanent magnet 201. Alternating current from the signal secondary SS is supplied through resistance 202, 115 and the slip-rings 203 to the armature coil 200. A pair of similar interrupter discs 204 and 205 are mounted on the shaft of the motor which drives the interrupter, each disc comprising a contact section 206, 90° in 120 arcuate length and an insulating section 270° in length indicated at 207. The two discs are arranged so that the contact sections 206 are 180° out of phase with each other, as indicated in the drawings. One 130

terminal of secondary TS is connected through wire 207 with a brush or sliding contact 208 bearing on the disc 204, the other terminal of this secondary being connected 5 through wire 19 with the armature 8^c of relay C. The secondary RS is connected in series with the primary of a transformer 209, so that the current induced in the secondary of this transformer will be similar to the 10 current from secondary TS but 180° out of phase therewith. One terminal of the secondary of transformer 209 is connected through wire 210 with brush 211 bearing on disc 205. The other terminal of this secondary is connected to wire 19 leading to the 15 armature 8^c. The other brushes 212 and 213 bearing respectively on the contact discs 204 and 205, parallel with the brushes 208 and 211, are connected by wire 12 with the armature 8^b of the relay C.

Referring now to diagram (1) of Fig. 5, the sine-wave designated TS indicates the alternating current induced in the secondary TS, and the sine-wave shown in broken lines 20 and designated RS indicates the alternating current derived from the transformer 209, this current being 180° out of phase with the current in secondary TS. The discs 204 and 205 of the rotary synchronous inter- 25 rupter are so set that they will cut out three-quarters of each cycle of each current, and retain only what may be termed the "rising half" of the positive side of each cycle, as indicated by the shaded areas in diagram 30 (1), and by the solid lines in diagram (2), which latter indicates graphically the pulsating direct current that will be transmitted through wires 12 and 19 to the armatures of relay C, and thence to the rails R and R', as hereinafter described. It will be noted that this current consists of a series of 35 similar rising pulsations, each of which is suddenly cut off at its peak, there being a dead interval corresponding to the length of one pulsation between each of the successive 40 pulsations.

Under normal conditions, that is, with each of the two advance blocks unoccupied, the armatures 8^a, 8^b, and 8^c will be swung 45 over to the right as hereinafter described, as indicated in dotted lines for block 1; or as indicated in solid lines at the left hand side of Fig. 1 for block 3. At such times a normal polarity pulsating current will flow from either the track secondary TS or transformer 209, and the interrupter K, through wire 12 to the pivot end of armature 8^b, right hand contact 13, wire 14, connections 15 to rail R adjacent the insulation 1 at the 50 exit end of block 2, through rail R to the entrance end of block 2, wire 9^c, coil 11' of relay D', wire 10', rail R', connection 16 adjacent the exit end of block 2, wire 17, right hand contact 18, armature 8^c, and wire 19, 55 connected to the pivot end of this armature

back to the secondary TS or the transformer 209. This circuit ordinarily provides what may be termed a "proceed normal polarity full-block-length current" to the track. The track relays D, D', etc. are sufficiently slow 70 acting to maintain their armatures in raised positions during the interruptions between pulsations of the track currents.

When the polarity of the actuating current for relay C has been reversed, as herein-after described, the armatures 8^b and 8^c will be swung to the left (as indicated in full lines for block 2), and an adverse polarity track circuit will be completed as follows: Track secondary TS or transformer 209, in- 75 terrupter K, wire 12, armature 8^b, left hand contact 20, wire 21, wire 22, to connection 23 to rail R', rail R' to the entrance end of block 2, wire 10', coil 11' of relay D', wire 9^c, rail R, connection 24, (opposite connection 80 23), wire 25 to left hand contact 26, armature 8^c, and wire 19 back to the track secondary TS or the transformer 209. This adverse polarity pulsating current may be indicated graphically by the broken lines in 85 diagram (2) of Fig. 5. The track connections 23 and 24 are spaced a suitable distance, for example, about twenty feet, from the insulations 1 at the exit end of block 2, so that a dead space of this length is provided adjacent the exit end of the block, to 90 which no current is supplied suitable for actuating the locomotive control devices when the normal polarity current is cut off, and adverse polarity current is being supplied to 95 the tracks. The circuit last described may be termed a "caution adverse polarity partial-block-length current". The intermediate contacts 27 and 28, which are engaged by the armatures 8^b and 8^c, when relay C is 100 deenergized, are connected by wires 29 and 30, respectively, with the wires 22 and 25, so that operatively the same caution adverse polarity circuit described hereinabove will be completed when the relay C is deenergized, and the armatures 8^b and 8^c are in 105 their intermediate positions. This may be termed a "repeating caution circuit".

The wayside signals S, S' and S'' are here shown as of an ordinary semaphore 115 type, actuated by a pair of coils 31 and 32. The semaphore S is shown in "stop" position, the semaphore S' in "caution" position, and the semaphore S'' in "proceed" position. A current flows when relay D is 120 energized from signal secondary SS through wire 33, armature 11^a, upper contact 34, wire 35, signal coil 31, and wire 36, back to the signal secondary SS. A similar parallel current flows from wire 35 through wire 125 37, armature 8^c of relay C, contact 38 or 38' when relay C is properly energized, wire 39, signal coil 32, and thence over wire 36 back to the signal secondary SS. When relay D is deenergized, as shown at the right of Fig. 130

1, the armature 11^a will fall and break the circuits to both signal coils 31 and 32 and the semaphore will fall to stop position, as indicated at S. When relay D' is energized 5 but relay C' is deenergized (as indicated in block 2), the circuit through signal coil 31' will remain complete, but the circuit through signal coil 32' will be broken, since armature 8^{a'} is not in contact with either of the contacts 38 or 38', and the semaphore will be moved to an intermediate or "caution" position, as indicated at S'. When both relays are energized, as shown at D'', and C'' in block 3, both coils 31'' and 32'' will be 10 energized and the signal will be moved to "proceed" position, as indicated at S''. The relative polarity or direction of flow of current through the coil 8 of relay C (and the consequent movement imparted to 15 the armatures 8^a, 8^b and 8^c), will depend upon the positions of the pole-changing armatures 11^b and 11^c of track relays D associated with the corresponding block and the block in advance, these armatures being 20 held up against respective contacts 40 and 41 when the coils 11 of the respective relays D are energized, and falling down upon the respective lower contacts 42 and 43 when the respective relays D are deenergized. 25 The energizing current for the coil 8 of relay C is derived from the signal secondary SS of the block in advance, and controlled by the neutral armature 11^a of the next following control unit (not shown in Fig. 30 35 1, but positioned beyond the right hand side thereof,) so in this instance we will describe the actuating circuit for coil 8' of relay C' for block 2, since this circuit is completely shown. Current flows from signal secondary SS through wire 33, armature 11^a if raised, contact 34, wire 35, wire 37, wire 44' (which may be an overhead cable leading to the next preceding unit), armature 11^b' of relay D' if raised, contact 40', wire 45', wire 46', coil 8' of relay C', wire 47', upper contact 41', armature 11^c' of relay D' if raised, and wire 48' which leads to the middle point of a resistance 49' connected across the power leads 4 and 5. The middle point 45 50 of a similar resistance 50 connected across the leads 4 and 5 adjacent the first described unit is connected by wire 51 with the wire 36 leading to the other end of signal secondary SS. The wire 48' might be connected directly with the wire 51, but since successive units are at a considerable distance from one another, a material economy is effected by utilizing the power lines 4 and 5 for this portion of the return circuit. It will be 55 noted that in the circuit just described, since relay D of block 1 is deenergized and the armature 11^a has been dropped, the circuit is open at 34, therefore relay C' is deenergized and its armature 8^{a'} has been dropped. 60 However, the coil 8 of relay C is energized,

since the armature 11^a of the track relay D of the "home" block or the block beyond block 1 at the right (not shown) is raised to complete this circuit. In this circuit, however, since the armatures 11^b and 11^c have been dropped by the deenergization of track relay D, the current flow will be reversed through coil 8 (from that already described for coils 8') since the circuit now runs from armature 11^b through contact 42, wire 47, 70 coil 8, wire 46, and lower contact 43 to the other armature 11^c. This will reverse the relative polarity of the current energizing relay C and cause the armatures 8^b and 8^c to swing to the left against contacts 20 and 26, 75 as shown in full lines. In the case of relay C', which is deenergized, the armatures 8^{b'} and 8^{c'} have fallen to the intermediate contacts 27' and 28'. 80

In describing the operation of this track apparatus, we will first assume that a stalled train, indicated at B, is in block 1. This train will shunt the current flowing in rails R and R' of block 1, so as to deenergize the track relay D and drop the armatures 90 11^a, 11^b and 11^c, all as shown in the drawings. The dropping of the armature 11^a will break the circuits to both signal coils 31 and 32 and the semaphore S will show a stop signal. As already described, the dropping of armature 95 11^a will also break the energizing circuit for relay C' of the preceding block, thus dropping the corresponding armature 8^{a'} and breaking the circuit to signal coil 32' so that semaphore S' will give a caution 100 signal. Since armature 11^{a'} of track relay D' is still elevated, the coils of relay C'' will be energized, attracting the corresponding armature 8^{a''}, and both signal coils 31'' and 32'' will be energized holding the semaphore 105 S'' in proceed position. Therefore a proceed signal will be given at the entrance of block 3, and a caution signal at the entrance of block 2, when a train occupies block 1.

The dropping of armatures 11^b and 11^c 110 of relay D has resulted, as already described, in reversing the relative polarity of the current energizing relay C and swinging the armatures 8^b and 8^c to the left so that a pulsating uni-directional current, termed the 115 "caution adverse polarity partial-block-length current" is flowing in block 2. Since relay C' is deenergized and the armatures 8^{b'} and 8^{c'} have been dropped against the intermediate contacts 27' and 28', a similar 120 repeating caution current of adverse polarity is flowing in block 3 which is a "proceed" block for the wayside signals, but a "repeating caution block" with relation to the train control mechanism. In each of 125 blocks 2 and 3 there is a "dead" section of about 20 feet adjacent the exit end of the block, in which no effective current is flowing. In block 4 a pulsating uni-directional current known as the "normal polarity full- 130

block-length current" is flowing, as in all other similarly conditioned unoccupied blocks of the track-way.

Referring now to Fig. 2 of the drawings, 5 the mechanism carried by the locomotive is diagrammatically illustrated, the locomotive being positioned over one of the "dead" sections of the track, with the brakes applied. It will be assumed that the locomotive is located in one of the blocks, such as block 2 or block 3 in Fig. 1, wherein adverse polarity current is being supplied to the rails R and R' in that portion to the left of the connections 23 and 24. At this particular time 10 the section of the rails occupied by the front portion of the locomotive is receiving no current suitable for actuating the controlling mechanism in the cab. The locomotive is indicated by the wheels shown at L. The 15 collector coils 52 and 52^a are wound around the soft laminated iron U-shaped cores 53 and 53^a, and are so wound that the currents induced in these coils by the track currents running in the opposite directions in the 20 two parallel rails R and R' will be added collectively in these coils, and will pass through wires 54 and 55 and charge the condensers 56, 57 and 214. Obviously the 25 direction, or polarity of this induced current will depend upon the polarity of the current flowing in the rails, and at the instance 30 noted in the drawings no effective current at all will be induced in the coils 52 and 52^a. It will be noted that the cores 53 and 53^a, 35 and the coils 52 and 52^a thereon, are mounted over and around the first pair of pilot 40 wheels L. When passing over one of the insulated joints 1 at the adjacent ends of track blocks, these wheels L will serve to 45 bridge the joints and the coils being positioned over the wheels, no break in the induced current will occur, that is, when similar currents are flowing in the adjacent blocks, as for example at the junction of block 4 and the block preceding block 4.

The improved power amplifier now to be described is designed to build up, in response to the weak currents induced in the coils 52 and 52^a, a pair of currents adapted to 50 alternatively control the direct current polarized relay M. The power amplifier preferably includes a tube 58 having a single filament 59, energized from the battery 60 through leads 67 and 68 as shown, a pair of 55 grids 61 and 62, and a pair of plates 63 and 64. Assuming that a so-called normal polarity pulsating current, (of the type indicated graphically in solid lines in diagram (2) of Fig. 5), is flowing in the rails R and 60 R', an alternating current of substantially the type indicated graphically in diagram (4) of Fig. 5 will be induced in the coils 52 and 52^a. This induced current will have 65 substantially the characteristics of a pulsating direct current, each cycle consisting

of a comparatively long increasing pulsation x of normal polarity, followed by a practically instantaneous reverse pulsation, or so-called "peak cycle", indicated at y. A similar current, but of reversed polarity, as 70 indicated in diagram (3) of Fig. 5, will be induced in the coils 52 and 52^a when the adverse polarity current is flowing in the rails R and R'. 75

The pulsation x, when produced by a 60 cycle alternating current, corresponds to one of the pulsations of a pulsating current having a frequency of 120, while the "peak cycle" y will correspond to a pulsation of very high frequency, for example 2000. The condenser 214 is tuned to the high frequency of the peak cycle current, whereas the condensers 56 and 57 are tuned to a frequency of 120. 80

Assuming that the induced current is flowing from coils 52 and 52^a through wire 85 55, a positive charge will be impressed upon the lower plate of condenser 57, and a negative charge upon the lower plate of condenser 56. The successive positive charges impressed upon the lower plate of condenser 57, 90 form negative charges upon the upper plate, which in turn impress positive charges upon the grid 61. In a converse manner a series of negative charges are impressed upon the grid 62. When the so-called adverse polarity current is flowing in the rails R and 95 R', the current induced in the coils 52 and 52^a will be reversed, so that grid 62 will receive the positive charges and grid 61 the negative charges. 100

The peak cycles induced by the sudden interrupting of the pulsating current in the rails will discharge through the properly tuned condenser 214.

One circuit extends from filament 59, wire 105 67, battery 60, wire 82, one actuating coil 83 of the relay M, and wire 81 to plate 63. A similar circuit extends from filament 59, wire 67, battery 60, wire 84, the other actuating coil 86 of relay M, and wire 85 to plate 110 64. When the grid 61 is positively charged and the grid 62 is negatively charged, a relatively strong pulsating current will flow in the coil 83, and a relatively weak pulsating current will flow in the opposite direction in coil 86, as indicated graphically at a and b respectively in diagram (5) of Fig. 5. On the contrary, when the grid 61 is negatively charged, and the grid 62 is positively charged, the stronger pulsating current will flow in coil 86 and the weaker current in coil 83, as indicated graphically at b' and a' respectively in diagram (6) of Fig. 5. The relay M, in the example here shown, comprises the soft iron U-shaped core 80, 115 having legs 78 and 79 about which the actuating coils 83 and 86 are respectively wound in opposite directions. The legs 78 and 79 terminate in pole pieces 76 and 77 adapted to attract the swinging armature 88, and also 120 125 130

the neutral armature, hereinafter described. The neutral armature will be drawn up whenever the pole pieces are energized, no matter what their polarity may be. The 5 polarity of swinging armature 88 is permanent, and it is pivoted at its upper end near the neutral magnetic portion of core 80. The armature 88 having a permanent polarity, it will be swung alternately from side to 10 side as the poles of the relay M are reversed. When the current of predominating strength is in coil 83, the armature 88 of relay M will be swung over to the right, as indicated in dotted lines in Fig. 2, and when 15 the current in coil 86 is the stronger, the armature will be correspondingly swung to the left as indicated in solid lines in Fig. 2.

The swinging armature 88 of relay M, when swung to the right by currents of 20 normal polarity, will engage the fixed contact 90, and when swung to the left by currents of adverse polarity, will engage the fixed contact 91. While swinging from one 25 of these positions to the other the armature 88 will momentarily engage an intermediate contact 92. The relay M is also provided with a neutral armature comprising two contact bars 89 and 97. When the relay M is energized, the armatures 89 and 97 will be 30 held up against the fixed contact members 93 and 95 respectively, and when the relay is deenergized the armatures will fall into engagement with the fixed contacts 94 and 96. When armature 97 is raised it also engages a second fixed contact 95', hereinafter referred to.

The electrical circuits of the locomotive are energized by the generator G mounted thereon. One terminal of the generator is 40 connected through wire 98 with the pivot ends of armatures 97 and 89, and the other side of the generator is connected by wire 100 with one side of each of the signal lamps 101, 102, and 103, adapted to give, respectively, green, red and yellow signal indications. The other sides of these lamps are 45 connected, respectively, as shown, with the fixed contacts 90, 92 and 91. Red lamp 102 is also connected with fixed contact 96, as shown. Under normal running conditions, when normal polarity current is present in the rails, the armature 88 will be held over 50 to the right against contact 90 and a circuit from the generator will be completed as follows: Wire 98, armature 97, contact 95, wire 99, armature 88, contact 90, green lamp 101, and wire 100, back to the negative side 55 of the generator. This will give a normal green running signal. When the train 60 passes into a caution block, the polarity of the current induced from the rails and operating relay M will be reversed, and the armature 88 will be swung over to the left against fixed contact 91, thus closing a circuit 65 similar to that just described through

the yellow caution signal light 103. It will be noted that in passing from its right hand to left hand position, the armature 88 will momentarily engage the contact 92, thus giving a red flash of lamp 102 as a further 70 warning signal. When no induced current is being received by relay M, the armature 97 will fall into engagement with contact 96, and a circuit through the red danger or 75 stop light 102 will be completed and maintained.

The valve V for controlling the brakes, comprises a valve block or chamber 104, in which is slidably arranged a double-seating angular slide member 105, having an operating rod 106 to which is affixed a plate 107 adapted to be held up by the magnets 108 against the action of the spring 109, which tends to move the valve member 105 to its lower position, as shown in the drawings. 80 Normally, with the brakes released, the slide member 105 will be held up by the magnets 108 with the plate 107 in its dotted line position. At the upper end of rod 106 is pivoted a contact plate 110, adapted in normal 85 raised position to engage the fixed contact 111, and when lowered, as shown in the drawings, engaging the fixed contact 112. When the valve member 105 is raised to normal running position, communication is 90 established from the air reservoir pipe 113, through ports 114 and 115 and the pipe 116 to the brake valve 117. When the magnets 108 are deenergized, the spring 109 forces 95 the slide member 105 down into the position shown in the drawings, to close the air reservoir ports 114 and 115 and to establish communication from the train line pipe 118, through pipe 119 and port 120 with the outlet 121 to the atmosphere. It will be 100 obvious from the drawings that when the magnets 108 are energized to raise the member 105, the port 120 will be closed to prevent train line exhaust, and ports 114 and 115 will be opened to provide reservoir pressure 105 to the brake valve to hold the brakes released. An outlet 122 is provided to allow 110 the escape of any air that may be trapped above the top of the sliding member 105. As the slide member 105 rises it will close the opening 122 to prevent the escape of 115 train line air. While the type of valve just described is preferred, it will be apparent that other suitable types of brake valves might be used, the movements of the valve member being actuated by the magnets 108 and the return spring 109.

As long as relay M is receiving current, either of normal or adverse polarity, the armature 89 will be held up against fixed contact 93, and a circuit for energizing the releasing magnets 108 will be completed, as follows: Generator G, wire 98 to the pivot end of the armature 89, contact 93, wire 123, wire 124 to the pivot end of swinging 125

contact plate 110, fixed contact 111, wire 125 to the coils of magnets 108, and wires 126 and 127 back to the generator G. Whenever the armature 89 is momentarily released by the deenergization of relay M, the circuit will be broken at 93, thus deenergizing magnets 108 and causing a brake application unless this action is forestalled by manual operation of the acknowledgment switch 128. The armatures 89 and 97 are slow-acting and even a momentary deenergization of the magnets 108 by breaking of the actuating current at 93 will be sufficient to permit the highly compressed spring 109 to move valve 105 downwardly and effect a brake application. It is only necessary that spring 109 act quickly enough to break the circuit at 111 before the contact is again reestablished at 93 or 94. Once the energizing circuit for magnets 108 has been broken at 111 it can only be reestablished by manual manipulation of one of the switches 135 or 141. In the example here shown, the acknowledgment switch 128 is in the form of a spring released plunger adapted to close the gap between the contacts 129 and 130, connected by wires 131 and 132, respectively, with the wires 98 and 124, thus forming a shunt circuit about the relay M. By pushing in the switch 128 while the locomotive is passing over a deenergized section of the track, the holding circuit for magnets 108 may be maintained while the armature 89 is out of contact with the fixed contact 93 or 94, the magnets 108 being sufficiently quick-acting to break the circuit at 111 while armature 89 is passing from contacts 93 to contact 94, if the switch 128 is not closed.

If the brake application is not forestalled, a circuit will be completed through the brake signal light 133, which may conveniently give a purple indication, as follows: From generator G through wire 98, armature 89, contact 94, wire 123, wire 124, swinging contact plate 110, fixed contact 112, wire 134, purple light 133 and wire 127 back to the generator. The light 133 will give a purple indication, as long as the brake application is taking place.

In case a brake application is not forestalled in time before passing over a "dead" section of the track by the manipulation of switch 128, provisions are made whereby the brakes may be reset provided the train is merely in a caution block or a repeating caution block, that is, providing the relay M is receiving induced current of either normal or adverse polarity. In such case, the armature 97 will be raised into contact with the fixed contact 95'. At such a time, by manipulating the resetting switch 135, which is adapted to close the gap between contacts 136 and 137, a resetting circuit through the magnets 108 will be completed as follows:

From generator G to wire 98, armature 97, contact 95', wire 138 to contact 136, resetting switch 135, contact 137, wire 140, wire 125, magnets 108 and wires 126 and 127 back to the generator G. After the brakes have once been reset, the contact plate 110 will be moved up against contact 111, thus completing the normal brake releasing circuit, and the switch 135 may then be released. However, if the brake application takes place under "stop" conditions, that is when the locomotive is in one of the dead sections at the exit end of a caution block, or is in an occupied block, the relay M will be completely deenergized and the armature 97 will not contact with the fixed contact 95', so that the resetting switch 135 will be ineffective to reset the brakes. In such an event, the brakes can only be reset by manipulation of the switch 141 which is located beneath the locomotive, or at a point which is only accessible after the train has been brought to a complete halt. The circuit through resetting switch 141 is as follows: From generator G, through wires 131 and 142, to fixed contact 143, switch 141, fixed contact 144, wire 145, wire 140, wire 125, magnet coils 108 and wires 126, 127, back to the generator G.

The usual double-heading cock 146 is provided in the train pipe line 118, and a train stop failure cock 147, under seal, is provided for normally closing the reservoir pipe 148 and opening the train line exhaust pipe 119.

In describing the general operation of this mechanism, I will first assume the condition shown in Fig. 1 of the drawings, a train B occupying stop block 1, and shunting the track circuit therein so as to deenergize the track relay D. A train approaching from the right will pass through proceed block 4, which is still receiving normal polarity full-block-length current, with the green running light showing in the cab, and no brake application will take place. As this train enters repeating caution block 3, as indicated at E, the wayside semaphore signal S' will still give a "proceed" signal, but since adverse polarity current is being supplied to the rails in block 3 and adverse polarity current will be induced in the locomotive to operate the relay M, the armature 88 will be swung from its right to its left position so that the green light will be extinguished and a yellow signal will be given by the lamp 103. This practically instantaneous change in polarity of coils 83 and 86 causes a reversal of the position of armature 88, but will not deenergize the coils sufficiently to release the neutral armatures 89 and 97 which will remain up in contact with the fixed contacts 93 and 95 respectively. This will be a caution signal to the operator that an obstruction occurs in the second block ahead, or perhaps in the first block.

ahead in case of a train backing thereinto. It will also indicate to the operator that a brake application will take place at the exit end of this block 3, in which he is now located, and he must forestall this application by closing the switch 128 as the train proceeds across the dead section between the points 23', 24' and the exit end of block 3. If the operator manipulates switch 128 in time, no brake application will take place, and as he enters block 2, a caution signal will be observed at semaphore S' and also the yellow caution light 103 will continue to show within the cab. This will inform the operator that the obstruction is within the next succeeding block. It will also be noted that as the train passes over the dead track section, or brake application point, at the end of block 3, the armature 97 will be released to make contact with the fixed contact 96 and give a red flash or signal through the temporary energization of lamp 102. This is a further warning to the operator that the brake application point is being crossed, and when the yellow signal resumes its caution indication within the cab, the operator will know that he may release the switch 128. In case the operator neglected to operate the forestalling switch 128 in time to avoid the brake application, the brakes may be reset from within the cab by closing switch 135 after the train has entered caution block 2. The train will now be at the position indicated at F.

35 After the train passes the points 23, 24 in caution block 2, no further induced currents will be transmitted to the relay M, either in this end portion of block 2 nor in any portion of block 1. Consequently a 40 brake application will immediately take place unless forestalled by closing the switch 128. If the automatic brake-application is forestalled the operator may bring the train to a halt in the usual manner by 45 manual operation of the brake valve 117 upon observing the continuous red stop indication. If the automatic brake application is not forestalled by closing switch 128, the brakes will be immediately applied, and 50 the switch 135 will now be ineffective, to reset the brakes since armature 89 is no longer in contact with fixed contact 95, the relay M being deenergized. The train will 55 now be stopped and the brakes can only be reset by manipulating the switch 141 which is not accessible from the cab. Upon entering stop block 1, the wayside semaphore signal S will also give a stop indication. It 60 will be noted that a yellow caution signal will be given in the cab throughout both of the two blocks preceding the occupied block, and that a red flash will take place at the exit end of each of these blocks. A brake application will also take place at the exit 65 end of each of these blocks, unless fore-

stalled by using switch 128. If the yellow signal resumes after a red flash, the operator will know that he is still within a caution block and may proceed if on the alert. Whenever the brakes are being applied, the purple light 133 will signal that fact to the operator.

In case an engine has fully entered an advance block, and a yellow light begins to show, with an immediate brake application, 75 this indicates that in one of the next two adjacent blocks the track circuit has been suddenly shunted or broken by an open switch, a broken rail or an advance train backing into that block. This brake application 80 occurs because the advance track relay's contacts will drop, and the moving of the pole changing armatures on the line relays from normal to adverse polarity contact position will provide an intermittent loss of track 85 current during such change, and the consequent momentary dropping of armature 89 on the engine will break the magnet circuit and cause the brake application. The brakes may now be reset by means of switch 90 135 in case the engine is merely within a caution block, but if the obstruction occurs within the block then occupied, this switch 135 will be ineffective and the train will be stopped. In any case, a shunting of the track circuit by an obstruction within the same block occupied by the engine will 95 cause an immediate brake application, and the brakes cannot be reset until the train has been halted.

100 Any temporary loss of track current and consequent deenergization or relay M will result in the dropping of armature 89, and thus breaking the energizing circuit for magnets 108 with a resultant brake application. However, when the locomotive passes from one block energized with normal polarity current to an adjacent block energized with adverse polarity current, (for example from block 4 to block 3), although 105 the polarity of relay M will be reversed to swing the armature 88 from right to left, the relay will be continuously energized sufficiently to maintain the neutral armature 89 in its raised position so that the energizing 110 circuit to magnets 108 will not be broken and no brake application will take place.

115 It will thus be observed that automatic brake applications take place at the exit ends of both caution and repeating caution blocks preceding an occupied block, and that such brake applications take place immediately at any point upon the track if the track circuits are shunted or broken by any cause in either the block occupied by the engine or in either of the next two advance blocks. These brake applications may be forestalled, or the brakes temporarily reset in case the obstruction or danger point is within one of the following blocks, but not 120 125 130 135

if the danger point is within the block then occupied. The system necessitates successive acknowledgments to prevent brake applications at the end of each block when the 5 train is running under danger conditions, that is, following a train in the same block or in one of the next two advance blocks. In case the trains are running within the same block and the forward train proceeds 10 into an advance block, the block occupied by the following train will change from stop to caution conditions and a brake application will occur immediately unless forestalled by switch 128. The brakes may, however, be reset by the running reset switch 15 135.

It will be evident from the foregoing description that by holding the switch 128 closed brake applications are prevented, and 20 it is only intended that this switch shall be closed momentarily, to bridge over the intervals when armature 89 is moving from one operative position to another. It will be apparent that if this switch 128 were held 25 closed permanently, or for an unauthorized length of time, many of the operations involved in this control system would be avoided. To prevent this, the modified form 30 of acknowledgment switch shown in Fig. 3 may be used, if considered necessary. The stem 149 extending from switch plate 128 carries the valve member 150, which fits 35 within the valve-block 151 so as to normally close the port 152 communicating with pipe 153 which leads from the air-brake system. When switch 128 is closed, the valve 150 will 40 be lifted to permit a small escape of air through the port 152, which will bleed the air system, so that if this switch 128 is held 45 closed for any material length of time (and the valve 150 thus held open), a brake application will occur due to the loss of air through port 152.

It is to be noted that when traffic 50 conditions change from "danger" to either "caution" or "clear", the engineer must again "acknowledge", since the armatures 89 and 97 move from their lower to their upper positions upon such a change in traffic conditions 55 and unless the engineer "acknowledge" solenoid 108 will become deenergized, as already described.

It will be noted that the track electrification is produced from a single alternating 60 current, and that only a single pulsating current will flow at any one time in the rails of any block, and only a single induced current is utilized to control the mechanism on the locomotive or other vehicle. At any one instant 65 the currents in all "proceed" blocks are flowing in the same direction, or are of the same polarity, whereas the currents in "caution" or "repeating caution" blocks will at that instant flow in the reverse direction, 70 or be of the opposite polarity. The induced

current in the vehicle will change its direction of flow or polarity in accordance with the position of the vehicle over the rails of either a proceed or caution block. Whenever the relay M is deenergized to drop the 70 armature 89, a brake-application will occur (unless forestalled). This will occur whenever conditions change from either proceed or caution to "stop". Also, whenever relay M is again energized to raise the armature 75 89, a brake application will take place. In other words, whenever the vehicle passes from an electrified to a non-electrified or "power-off" section of trackway, or when it passes back onto an electrified section, a 80 brake application will occur unless forestalled. Such conditions will be indicated by the change from either a green or yellow to a red indication, or the change from a red indication back to a yellow or green. Whenever the purple light is illuminated a brake-application is taking place. In such case, if a yellow or green light is burning, the reset switch 135 will be effective to release the 85 brakes while the vehicle is running, but 90 if the red signal persists, the reset switch 135 will be inoperative, and the switch 141 must be used to reset the brakes after the train has been brought to a complete stop.

The single current used in this system has 95 triple controlling characteristics, that is it controls (1) the wayside semaphore signals, (2) the position indicating signals in the cab, and (3) the brake-applying mechanism. A signal track-relay and a single line-relay 100 for each block cooperate to control the polarity of the current supplied to the rails, and to give the proper wayside signal for that block. A single relay in the cab controls both the cab position-indicating signals 105 and the brake controlling mechanism.

This system makes possible the bringing 110 of advance information of the conditions existing in advance blocks to the operator by means of cab lights, substantially as found along the wayside, and makes possible the eventual discard of all main track wayside signals.

It will be noted that the second block preceding an occupied or "stop" block is 115 simultaneously a "proceed" block in so far as the wayside or semaphore signals are concerned, and a "repeating caution block" with relation to the cab-position-indicating mechanism and the brake control mechanism. 120 By properly interpreting the combined signals given by the semaphores and by the cab lights, the operator can estimate with fair accuracy the distance from the stop point, that is, he will know approximately 125 whether he is one or two blocks distant from the location where stop conditions prevail.

With vehicles so equipped, upon entering 130 non-electrified tracks from electrified

tracks, the automatic brake controlling apparatus may be completely released by temporarily closing the forestalling switch 128. This acknowledgment switch must again be 5 operated when the vehicle again enters the electrified track in order to prevent a brake application. In this latter case, if the acknowledgment is neglected, the brakes may be reset by operating the running 10 reset switch 135.

As a positive check against foreign current interference during a stop condition, a brake application occurs during the movement of armature 89 from lower contact 94 15 to upper contact 93, when the apparent conditions change from a stop to a caution or to a proceed circuit; this also guards against an engineer acknowledging a stop and continuing at high speed in the same block with 20 another train, since the advance train passing into the next block circuit provides in the rear block caution current to the fast moving train therein and gives a brake application to such train at any part of that 25 block so that the second train has as much braking distance as possible.

The running reset circuit through switch 135 will avoid an actual stop of the train if the operator is alert to operate this switch, 30 but this action will not actually interfere with the brake applying means, since there is continuous possibility of further brake applications within the same block that has already given a brake application condition. 35 In other words, the closing of switch 135 will be effective to permit the release of the brakes, but this circuit will be broken even though switch 135 is closed in case relay M is deenergized and the armature 89 is 40 dropped. Thus the stopping of the train under actual danger conditions cannot be avoided by closing the switch 135.

I claim:

1. In combination with a trackway divided into blocks, a vehicle adapted to travel on the rails of the trackway, brake controlling means on the vehicle, and position-indicating signals on the vehicle, a source of alternating current, means for supplying a single current derived from this source to each block of the trackway, means for reversing the polarity of this current in a portion of the block and cutting off the current in the remainder of the block in response to advance track conditions, and means on the vehicle for receiving a single induced current from the rails which is broken or changes its polarity in conformity with the track current, and utilizing this current to control the brake-controlling means and the position-indicating mechanism.

2. In combination with a trackway divided into blocks, a vehicle adapted to travel on the rails of the trackway, position-indicating means on the vehicle for giving

proceed, caution and stop signals, a source of alternating current, means for supplying a single current derived from this source to each block of the trackway, means for reversing the polarity of this current in a portion of a block and cutting off the current in the remainder of the block in response to advance track conditions, and means on the vehicle for receiving a single induced current from the rails which is broken or 75 changes its polarity in conformity with the track current, and utilizing this current to control the position-indicating means.

3. In combination with a trackway divided into blocks, a vehicle adapted to travel 80 on the rails of the trackway, and means on the vehicle controlled by currents induced from the rails, a single source of alternating current, connections for transmitting from this source a separate pulsating unidirectional current to the rails in each of a plurality of adjacent blocks, and means for reversing the direction of flow of this pulsating current in one block in response to stop 85 conditions existing in an adjacent block. 90

4. In combination with a trackway divided into blocks, a vehicle adapted to travel on the rails of the trackway, and means on the vehicle controlled by currents induced from the rails, a single source of 95 alternating current, connections for transmitting from this source a separate pulsating unidirectional current to the rails in each of a plurality of adjacent blocks, and means actuated in response to stop 100 conditions existing in an advance block for reversing the direction of flow of this pulsating current in the preceding block.

5. In combination with a trackway divided into blocks, a vehicle adapted to travel on the rails of the trackway, and means on the vehicle controlled by a single current induced from the rails, a source of alternating current, connections for transmitting from this source a separate current to the 110 rails in each of a plurality of adjacent blocks, and means actuated in response to stop conditions existing in an advance block for reversing the polarity of the current in each 115 of the two preceding blocks.

6. In combination with a trackway divided into blocks, a vehicle adapted to travel on the rails of the trackway, and means on the vehicle controlled by a single current induced from a single current in the 120 rails, a source of alternating current, connections for transmitting from this source to each of a plurality of adjacent blocks, either a pulsating current of normal polarity to the full length of the block, or a pulsating 125 current of adverse polarity to a portion of the block, and means for reversing the polarity of the current in one block in response to stop conditions existing in an advance block. 130

7. In combination with a trackway divided into blocks, a vehicle adapted to travel on the rails of the trackway, and means on the vehicle controlled by a single current induced from a single current in the rails, a source of alternating current, connections for transmitting from this source to each of a plurality of adjacent blocks, either a pulsating current of normal polarity to the full length of the block, or a pulsating current of adverse polarity to a portion of the block, and means for reversing the polarity of the current in one block in response to stop conditions existing in either of the next two advance blocks.

8. In combination with a trackway divided into blocks, a vehicle adapted to travel on the rails of the trackway, and means on the vehicle controlled by a single current induced from a single current in the rails, a source of alternating current, connections for transmitting from this source to each of a plurality of adjacent blocks, either a pulsating current of normal polarity to the full length of the block, or a pulsating current of adverse polarity to a portion of the block, and means actuated in response to stop conditions in an advance block for reversing the polarity of the current in the two preceding blocks.

9. In combination with a trackway divided into blocks, a source of alternating current, means for supplying from this source a single uni-directional pulsating current to the rails in a block, and means for changing the polarity of this current in response to changes in advance track conditions, a vehicle adapted to travel on the rails, means on the vehicle for receiving an induced current conforming to the current then existing in the rails, amplifying means on the vehicle responsive to the induced current, a relay having two actuating coils energized from the amplifying means, the relay having an armature movable to a plurality of positions and a plurality of position-indicating signals controlled by the armature of the relay.

10. In combination with a trackway divided into blocks, means for suitably electrifying this trackway, a vehicle adapted to travel on the rails of the trackway, and brake-controlling mechanism on the vehicle, means controlled electrically from the trackway whereby when stop conditions exist in an advance block, a brake application will take place at the exit end of each of the two preceding blocks and running-reset means on the vehicle whereby the brakes may be released following a brake-application in the second preceding block, this means being ineffective after the vehicle has entered the block in which stop conditions exist.

11. In combination with a trackway di-

vided into blocks, means for suitably electrifying this trackway, a vehicle adapted to travel on the rails of the trackway, and brake-controlling mechanism on the vehicle, means controlled electrically from the trackway whereby when stop conditions exist in an advance block, a brake application will take place at the exit end of each of the two preceding blocks, manually-operable means on the vehicle for forestalling these brake-applications, and manually operable running-reset means on the vehicle whereby the brakes may be released if a brake application is not forestalled in the second preceding block, this reset means being ineffective after the vehicle has entered the block in which stop conditions exist.

12. In combination with a trackway divided into blocks, means for suitably electrifying this trackway, a vehicle adapted to travel on the rails of the trackway, and position-indicating signal mechanism on the vehicle adapted to give either proceed, caution or stop signals, means controlled from the trackway in response to stop conditions existing in an advance block for causing a caution signal to be given while the vehicle is in the next preceding block, also a repeating-caution signal to be given while the vehicle is in the second preceding block, and a stop signal to be momentarily given at the end of this second block.

13. In combination with a trackway divided into blocks, means for suitably electrifying this trackway, a vehicle adapted to travel on the rails of the trackway, and position-indicating signal mechanism on the vehicle adapted to give either proceed, caution or stop signals, means controlled from the trackway in response to stop conditions existing in an advance block for causing a caution signal to be given while the vehicle is in the second block preceding the advance block, and a stop signal to be momentarily given at the end of this second block.

14. In combination with a trackway divided into blocks, a vehicle adapted to travel on the rails of the trackway, brake controlling means on the vehicle, position-indicating signals on the vehicle, a generator on the vehicle for supplying actuating current to the brake controlling means and the position-indicating signals, a source of alternating current, means for alternatively supplying from this source a pulsating current to the full length of the rails in each block or a pulsating current of reverse polarity to a portion of the rails only, means acting in response to stop conditions existing in an advance block for determining the polarity of the current supplied to the block, means on the vehicle for receiving a single induced current from the current then existing in the rails, and means

on the vehicle for utilizing this current to control the brake-applying means and the position-indicating signals.

15. In combination with a trackway divided into blocks, a vehicle adapted to travel on the rails of the trackway, brake controlling means on the vehicle, position-indicating signals on the vehicle, a generator on the vehicle for supplying actuating current to the brake controlling means and the position-indicating signals, a series of wayside signals one at the entrance to each block, a source of alternating current, means for supplying from this source either a pulsating current of normal polarity to the full length of the rails in each block or a pulsating current of reverse polarity to a portion of the block rails only, means acting in response to stop conditions existing in an advance block for determining the polarity of the current supplied to the block and for also actuating and controlling the wayside signals, means on the vehicle for receiving a single induced current from the current then existing in the rails, and means on the vehicle for utilizing this current to control the brake-applying means and the position indicating signals.

16. In combination with a trackway divided into blocks, a vehicle adapted to travel on the rails of the trackway, and means on the vehicle controlled by currents induced from the rails, a single source of alternating current, and a means for each block for transmitting from the alternating current a pulsating unidirectional current to the rails of the block, comprising a transformer having a primary energized by the alternating current, and two secondaries, and means actuated by the alternating current from one secondary for interrupting the current from the other secondary.

17. In combination with a trackway divided into blocks, a vehicle adapted to travel on the rails of the trackway, and means on the vehicle controlled by currents induced from the rails, a single source of alternating current, and a means for each block for transmitting from the alternating current a pulsating unidirectional current to the rails of the block, comprising a transformer having primary energized by the alternating current, and two secondaries, a rotary interrupter actuated by the alternating current

from one secondary, the interrupter rotating 55 synchronously with the alternating current and serving to transmit to the rails only similar portions of each cycle of the current from the other secondary.

18. In combination with a trackway divided into blocks, a vehicle adapted to travel on the rails of the trackway, and means on the vehicle controlled by currents induced from the rails, a single source of alternating current, and a means for each block for 60 transmitting from the alternating current a pulsating unidirectional current to the rails of the block, comprising a transformer having a primary energized by the alternating current, and three secondaries, an interrupter actuated by the current induced in one secondary, and a transformer for changing the phase of the current induced in a second secondary, the interrupter serving to transmit to the rails only similar portions of 70 each cycle of the currents induced in the second and third secondaries.

19. In combination with a trackway, a vehicle adapted to travel on the rails of the trackway, control means on the vehicle responsive to a current induced from the rails, a source of alternating current, means for transmitting from this source a pulsating unidirectional current to the rails, and means for reversing the direction of this 80 pulsating current flow in one portion of the trackway in response to stop conditions existing in an adjacent portion of the trackway.

20. In combination with a trackway divided into blocks, a wayside signal at the entrance to each block, a vehicle adapted to travel on the rails of the trackway, and means on the vehicle controlled by currents induced from the rails, a single source of 90 alternating current, and a transformer for each block having a primary energized from the alternating current source, and a plurality of secondaries, and means actuated by the several currents induced in the secondaries for actuating the wayside signals and transmitting a pulsating unidirectional current to the rails of each block, and means cooperating with the last mentioned means for reversing the current in one block in response to advance track conditions. 100 105

RUSSELL V. APPLETON.

CERTIFICATE OF CORRECTION.

Patent No. 1,704,116.

Granted March 5, 1929, to

RUSSELL V. APPLETON.

It is hereby certified that error appears in the printed specification of the above numbered patent requiring correction as follows: Page 9, line 100, for the word "signal" read "single"; and that the said Letters Patent should be read with this correction therein that the same may conform to the record of the case in the Patent Office.

Signed and sealed this 2nd day of April, A. D. 1929.
